UNITED STATES PATENT OFFICE.

FRED A. BOGAR, OF DENISON, TEXAS.

DESIGN FOR A TACK OR NAIL.

SPECIFICATION forming part of Design No. 27,570, dated August 24, 1897.

Application filed July 8, 1897. Serial No. 643,908. Term of patent 14 years.

To all whom it may concern:

Be it known that I, FRED A. BOGAR, a citizen of the United States, residing at Denison, in the county of Grayson and State of Texas, 5 have invented a new and original Design for a Tack or Nail, of which the following is a specification.

This invention relates to a new and original design for a tack or nail; and it has for 10 its object to provide a design of this character that shall be both useful and ornamental.

The leading feature of the design resides in a tack or nail having a straight shank tapering to a point and provided at one end 15 with a circular head disposed at right angles to the shank and having a flat outer face and a smaller concentric circular offset at its inner side, said circular offset having a flat face disposed at right angles to the shank.

20 In the drawings, Figure 1 is a perspective view of a tack or nail embodying the herein-described design. Fig. 2 is a similar view showing a reverse position of the tack or nail. Fig. 3 is a side view of the tack or nail.

Referring to the accompanying drawings, 25 the numeral 1 designates a tack or nail essentially comprising a straight shank 1^a, provided at one end with a circular head 2. The shank 1^a of the tack or nail tapers to a point, and the head 2 thereof is disposed at right angles 30 thereto, said head being provided with a flat outer surface 3 and at its inner side next to the shank with a smaller concentric circular offset 4. The offset 4 is provided with a flat face 5, disposed at right angles to the shank. 35

What I claim is—

The design for a tack or nail herein shown and described.

In testimony that I claim the foregoing as my own I have hereto affixed my signature in 40 the presence of two witnesses.

FRED A. BOGAR.
